PORTABLE RANGE AND BARBECUE GRILL COMBINATION OR SIMILAR ARTICLE

Renor S. Faidy, Jefferson County, Ky., assignor to General Electric Company, a corporation of New York

Filed Mar. 30, 1960, Ser. No. 59,958

Term of patent 14 years

(Cl. D81—10)

Figure 1 is a side perspective view of a portable range and barbecue grill combination or similar article embodying my new design, taken from the range end thereof;

The essential features of the design reside in the portions shown in full lines.

I claim:

The ornamental design for a portable range and barbecue grill combination or similar article, as shown and described.
